TERMINAL FOR EDGEWISE WOUND RESISTORS

Filed Nov. 20, 1935

UNITED STATES PATENT OFFICE

2,050,221

TERMINAL FOR EDGEWISE WOUND
RESISTORS

Joseph F. Frese, Baltimore, Md., assignor to
Monitor Controller Company, Baltimore, Md.,
a corporation of Maryland

Application November 20, 1935, Serial No. 50,795

4 Claims. (Cl. 201—63)

This invention relates to terminals for rheostat coils composed of metal ribbon wound on edge and mounted on bars which are attached at their ends to cross-bars of a rheostat frame. The flat metal ribbons are not flexible so that they can be bent easily in any direction like round conductors, and therefore the terminal is designed for easily securing the ends of edgewise wound resistors thereto. In my co-pending application Serial Number 25,328, filed June 6, 1935, I have shown a terminal for the same purpose as the terminal of the present invention but which it is necessary to place in one position on a cross-bar of the rheostat frame to connect to one end of a coil and in an inverted position on an opposing cross-bar to connect to the opposite end of the coil. The terminal of the present invention is an improvement upon the terminal shown in said application in that it is so constructed that it may be used in the same position at either end of the coil, and it also embodies an improved arrangement of the part of the terminal to which conductors other than the resistance coil may be attached, by inclining this part with respect to the part to which the coil is connected, instead of extending the first mentioned part at a right angle to the second, as disclosed in said application.

In the accompanying drawing,

Fig. 1 is a plan view of two edgewise wound resistance coils mounted in a frame, the ends of the coils being connected to terminals of the present invention;

Fig. 2 is a section on the line 2—2 of Fig. 1;

Fig. 3 is a left-hand end view of Fig. 1;

Fig. 4 is a perspective view of the two parts of the terminal;

Fig. 5 is a central section through the cap on the line 5—5 of Fig. 4, and,

Fig. 6 is a perspective view of a fitting to which conductors may be attached.

Referring to the drawing, *a* and *a'* indicate resistance coils made of metal ribbon wound on edge. The coils are supported on cores, each consisting of a flat metal bar *1* having a toothed insulating covering *2* onto which the coil is threaded and the ends of the flat bars are mounted upon cross-rods *3* and *4*, the cross-rods being surrounded by a tube of insulating material *5* which insulates them from the various parts which they support. The cross-rods extend through flat supporting members *6* and through the ends of flat side bars *7* which connect the supporting members together to form a frame, the parts being secured by nuts on the ends of the cross-rods, as shown.

The terminals *B* for the edgewise wound coils are mounted on the cross-rod *3* and similar terminals *B'* are mounted on the cross-rod *4*. One of these terminals is shown in detail in Fig. 4. The terminals on each cross-rod are spaced from the sides of the frame by spacing members *8*. Fittings *C* and *C'* to which conductors may be attached are arranged between the coil terminals. One of these fittings is shown in Fig. 6. The several parts on the cross-rods, which are insulated from the rods by the insulating tubes *5*, are insulated from one another by insulating washers *9*. Frames, as shown, carrying any desired number of resistance units, may be arranged with either side uppermost and mounted upon similar frames to form a bank of resistors as illustrated in my application above referred to.

The feature of novelty in the present invention resides in the structure of the terminals *B*, *B'*. Each terminal comprises a unitary member *b*, a cap *b'* and a bolt for securing these members together. In Fig. 4, for the purpose of illustrating its details, the member *b* is shown inverted with respect to the positions of the corresponding members in the assemblages, Figs. 1 to 3. The member *b* comprises an elongated relatively flat rectangular part *10* having its edges tapering toward both ends, as shown at *10a*, and having a central longitudinal bore *10b* extending through it to receive a clamping bolt *11*. Bosses *11* extend laterally from the opposite sides of the part *10* midway between its ends and a hole *12*, adapted to receive a supporting rod of the frame, extends through said bosses at a right angle to the bore *10b* and at one side thereof. A projection *13* inclines laterally from said bosses away from the part *10* and extends beyond one end thereof, this projection comprising the parallel arms *13a* and the wall *13b* connecting the outer ends of said arms. The wall has a slot *13c* midway between its arms and it has a flat outer surface *13d* which is preferably substantially parallel with the longitudinal axis of the part *10*. The arms and the wall form a socket to receive the head of a bolt *14* and prevent the bolt from turning, while the slot receives the shank of the bolt. The cap *b'*, which forms a part of the connector, is adapted to fit over either end of the part *10* and it has opposed walls tapering as shown at *15* to correspond with the tapering surfaces *10a* of the part *10*. The cap also has a slot *16* through which the end of a resistor ribbon may be extended and a hole *18* through which a bolt *17* may be inserted into the bore *10b* to draw the cap onto the part *10*.

One of the fittings *C* is shown in detail in Fig. 55

6 as comprising a hub portion 10 having an axial bore 20 to fit over a cross-rod of the frame, and a socketed projection 18 in all substantial respects the same as the socketed projection 13 on the connector members 8.

In the drawing, the terminals B, B' for each coil are arranged at the same side of the axis of the coil in line with its convolutions with the part 10 of each terminal arranged vertically and the part 18 inclined downwardly. As arranged, the downwardly extending portion of the end convolution 28 of the coil a' extends through the slot in the cap 8' which is placed over the lower end of the part 10 of terminal B and the end of the coil is clamped tightly against the tapering face of said part by the cap and the bolt 17 which extends upwardly through the cap and the part 10 and is provided with a nut 17' by which the bolt can be tightened. The upwardly extending portion of the convolution 28 at the opposite end of the coil passes through the cap 8' which is placed over the upper end of the part 10 of the terminal B' and the bolt 17 extends downwardly through the cap and said part and clamps the end portion 25 of the coil against the sloping face of said part.

Thus, it will be seen that as the part 10 of the terminal has flat tapering faces at both ends, it is only necessary to change the position of the cap in order to clamp a downwardly turned coil end or an upwardly turned coil end to the terminal body. Either one or both of the terminal bodies shown in Fig. 2 might be inverted so that the inclined parts 18 would extend upwardly instead of downwardly and the connection of the coil ends to the terminals would be made in the same way, as the part 10 of each terminal tapers at both ends and the cap fits either end. For an upwardly extending coil end, the cap would be applied to the upper end of part 10 and for a downwardly extending coil end, the cap would be placed on the lower end of the part 10.

As the coil terminals are arranged with the socketed projections 18 inclined downwardly, the fittings C, C' are arranged with the corresponding projections 21 inclined upwardly. These fittings are used for connecting conductors to leads or taps extending from intermediate parts of the resistance coils. Thus, for illustration one end of a flat conductor 24 is connected to a member 25 which is clamped to a convolution of the coil a', while the other end of said conductor is secured in the socket of the fitting C' by a bolt 26 which also extends through a terminal 27 of a wire or cable, not shown. In a bank of resistors 55 one of these fittings will be arranged on each supporting rod between adjacent coil terminals, and they may be used for supporting conductors or not, as may be desired. In the drawing, the fitting C is shown without a conductor attached to it.

By inclining the socketed projections of the coil terminals in one direction, as downwardly, and the projections of the fittings C, C' in the opposite direction, as upwardly, the electrical devices attached to the terminals and to the fittings are spaced apart and are accessible for attachment or removal, without interference.

What I claim is:

1. A terminal member for an edgewise wound helical resistance coil comprising a unitary metal

body including an elongated part tapering at both ends and having a central longitudinal bore, a hole to receive a supporting rod extending through the central part of said body at a right angle to said bore and at one side thereof, a cap 5 adapted to fit over either of said tapering ends and having a corresponding internal taper, said cap having a slot to receive one end of the coil and a hole to receive a bolt, and a bolt adapted to extend through the cap and into said longitudinal bore to draw the cap on to the tapering end to which it is applied.

2. A terminal member for an edgewise wound helical resistance coil comprising a unitary metal body including an elongated part tapering at 15 both ends and having a central longitudinal bore, oppositely extending bosses at the sides of said part midway between its ends, a hole to receive a supporting rod extending through said bosses at a right angle to said bore and at one side 20 thereof, a cap adapted to fit over either of said tapering ends and having a corresponding internal taper, said cap having a slot to receive one end of the coil and a hole to receive a bolt, and a bolt adapted to extend through the cap 25 and into said longitudinal bore to draw the cap on to the tapering end to which it is applied.

3. A terminal for an edgewise wound helical resistance coil comprising a unitary metal body having an elongated portion tapering at both ends 30 and having a central longitudinal bore, a hole to receive a supporting rod extending through the central part of said body at a right angle to said bore and at one side thereof, a projection inclining laterally from the central part of said 35 elongated portion at a right angle to the axis of said bore and extending beyond one end of said portion and constituting a socket having a wall with a flat outer face, said wall having an opening therethrough to receive a bolt, a cap adapted 40 to fit over either of said tapering ends and having a corresponding internal taper, said cap having a slot to receive one end of the coil and a hole to receive a bolt, and a bolt adapted to extend through the cap and into said bore to draw the cap 45 on to the tapering end to which it is applied.

4. A terminal member for an edgewise wound helical resistance coil comprising a unitary metal body including an elongated part tapering at 50 both ends and having a central longitudinal bore, oppositely extending bosses at the sides of said part midway between its ends, a hole to receive a supporting rod extending through said bosses at a right angle to said bore and at one side 55 thereof, a projection inclining laterally from said bosses away from said part and extending beyond one end thereof and constituting a socket having a wall with a flat outer surface, said wall having an opening therethrough to receive a bolt, 60 a cap adapted to fit over either of the tapering ends of said part and having a corresponding internal taper, said cap having a slot to receive one end of the coil and a hole to receive a bolt, and a bolt adapted to extend through the cap 65 and into said longitudinal bore to draw the cap on to the tapering end to which the cap may be applied.
